Attest.

UNITED STATES PATENT OFFICE.

HERBERT W. DAY, OF WOLLASTON, MASSACHUSETTS, ASSIGNOR TO SPRAY PAINTING & FINISHING EQUIPMENT SALES CO., A CORPORATION OF MASSACHUSETTS.

TOOL FOR APPLYING COATING.

Application filed April 1, 1922. Serial No. 548,696.

This invention relates to tools or apparatus for applying coating to surfaces and in its preferred embodiment is an improvement upon the construction disclosed in my Patent No. 1,172,233, dated February 15, 1916, the said tool or apparatus desirably functioning in accordance with the principles disclosed in said patent.

The coating, if a liquid, may be a paint, 10 japan, varnish or other suitable coating medium, or it may if desired be a solid in powdered form, and the material or surface to which it is to be applied may be of any character, such, for example, as wood, metal 15 or other material.

Referring more particularly to the drawings, wherein I have represented two embodiments of my invention;

Fig. 1 is a vertical central section taken 20 through the tool or apparatus;

Fig. 2 is a front elevation of a part only 25 of the apparatus shown in Fig. 1;

Fig. 3 is a view similar to Fig. 1 of another embodiment of my invention, and 30 wherein a container is attached to the body of the tool; and

Fig. 4 is a vertical section taken at right 35 angles to the section line of Fig. 3 looking toward the left in said Fig. 3 and representing the vent valves.

Referring first to that form of my invention shown in Fig. 1, the body of the tool is indicated at 1, the handle portion 2 being desirably integrally formed with the body 35 portion and having therein a longitudinal passage 3 for the paint or other coating material and a similar passage 4 for the air or other motive agent. The coating material and the motive agent are desirably supplied under pressure from some suitable 40 source in a manner which need not be more particularly described and which may be substantially the same as disclosed in my Patent No. 1,321,614, dated November 4, 45 1919.

The air or other motive agent entering the passage 4 is admitted into a valve chamber 5 here shown as extending transversely of the handle portion 2 and at an acute angle

to the axis thereof. Within said chamber 5 is threaded a bushing 6 having a valve seat 7 against which is adapted to be seated a valve 8 normally held closed by a suitable coil spring 9. The said valve is provided with a stem 10 extending through a packing 11 threaded into a suitable socket or recess in the end of the bushing. The end of the valve stem 10 is threaded as indicated at 12 to receive thereon the nut 13 and the yoke 14 which as indicated in dotted lines extend on both sides of the handle portion 2 to the front thereof where the ends of the yoke are received upon a transverse pin 15 by which the said yoke is pivotally connected to a trigger like operating lever 16 pivoted at 17 upon suitable ears on the front edge of the handle portion 2. Said operating lever 16 may be provided with a forwardly extending arm 16' for the attachment of other operating devices for controlling the operation of the tool at a distance. The bushing 6 is provided with a transverse passage 18, which when the valve 8 is opened admits the air or other motive agent into a chamber 19 which is in communication with a second 70 chamber 20 forming a continuation thereof as clearly shown in Fig. 1.

Desirably I provide means to heat the motive agent in its passage to the point of discharge. While any suitable means may 80 be provided for this purpose, I have herein represented an electrical resistance coil 21 which is seated in the chamber 19 and desirably closely fits the internal spiral flange 22, by which the entering air or other motive 85 agent is compelled to circulate about the coil on its way to the chamber 20. The said resistance coil is provided with two terminals 23, 24, which extend to a suitable plug or bushing 25. The coil and bushing are held 90 in place by a cap 26 threaded at 27 into the end wall of the chamber 19.

The body 1 is provided with a part 28 desirably integral therewith and transversely extending with respect to the handle portion 1. The said part 28 is herein shown as provided with a longitudinally extending passage 29, here shown as of two diameters

and receiving a correspondingly shaped valve member 30. Said valve member is received in the chamber 29 with sufficient looseness to admit the passage of the air or other motive agent about the frame and into a transversely extending through passage 31, itself communicating about midlength with the axial passage 32 that itself communicates with the open air at its forward or left hand end viewing Fig. 1, thereby permitting at the proper time the discharge of of the air or other motive agent against the film like coating material in a manner fully disclosed in my said prior patent and not herein necessary more fully to refer to.

Near its forward end the valve member 30 passes through and is supported by a plug or bushing 33, which is externally threaded as indicated at 34 into the part 28 of the body, where the passage 29 is of maximum diameter. Desirably in the rear of the bushing 33 are provided a series of disk like washers or packing members 35.

The part 28 is also provided with a longitudinally extending passage 36 which at its forward end is in communication with the space 37 within the inner cap 38 shown as internally threaded at 39 onto the externally threaded part 28. The said cap 38 at its forward end is provided with an axial opening 40 receiving the forward end of the valve member 30, the latter serving to close said opening when in the position shown in Fig. 1.

Outside the cap 38 is a cap 41 shown as internally threaded at 42 onto a differentially threaded ring 43, the latter constituting a closure for a passage 44 that supplies supplemental air from the main air supply. Inasmuch as the means for controlling the supplemental air supply may be substantially the same as that shown in my Patent No. 1,369,520, dated February 22, 1921, it is unnecessary more fully to describe the same, it being merely desirable to state that the supplemental air jets are discharged through the openings 45, 46 onto the discharged coating material and air or other motive agent issuing from inside the cap 38 and through the valve member 30.

I provide desirably motive agent controlled means for opening and controlling the closing of the said valve member 30. For this purpose I have herein represented a flexible diaphragm 47 of any suitable material and which is held in place by a cap-like member 48 having an external thread 49 received in the internally threaded flanged rear end of the part 28. The outer portion of the diaphragm 47 being held immovable by the engagement of said cap-like member 48 throughout its entire periphery, said diaphragm presents an efficient seal against leakage of the motive agent, and obviates the use of packing or the like, the present inven-

tion being an improvement in this and other respects over the construction disclosed in my Patent No. 1,401,397, dated December 27, 1921. The valve member 30 is threaded at its rear or right hand end viewing Fig. 1, as shown at 50, and it passes through the diaphragm, which is otherwise unperforated, said valve member 30 being held in position by a nut 51 at one face of the diaphragm and two nuts 52 at the opposite face thereof, a washer 53 being positioned between the two nuts 52. In this manner the valve member 30 may be adjusted relatively to the diaphragm if necessary, to compensate for wear at the outer or paint orifice closing end of said valve member. Bearing against the washer 53 is a coiled spring 54, the opposite end of which bears against a washer or ring 55 which may be adjusted in position by means of an elongated nut 56 threaded at 57 into an axial opening in the cap-like member 48. In this manner the tension or compression of the spring 54 may be varied as required in connection with varying pressures of the air or motive agent available.

Desirably I provide means constituting a stop or abutment for the inward movement of the valve member 30 and of the diaphragm. For this purpose I have herein represented a motion limiting pin 58, externally threaded as indicated at 59 into the elongated nut or threaded sleeve 56. The position of the limiting pin may be varied by rotating it to the desired extent, and in this manner the extent of movement of the valve member 30 to the left viewing Fig. 1 may be controlled. It is noted that by unscrewing the cap-like member 48 the entire diaphragm and paint control valve assembly may be removed rearwardly as a unit.

With the parts constructed as described the air or other motive agent is admitted through the passage 4 past the valve 8 and thence into the chambers 19, 20 where it acts upon the diaphragm 47 at the forward or left hand side thereof viewing Fig. 1 and thus opens the valve member 30, the air having previously entered the passages 31, 32, so that instantly upon the opening of the valve member 30 the discharging air strikes the coating material which is inside the cap 38, and discharges the same in a finely comminuted mass as fully disclosed in my said patent. Desirably the paint supplied through the passage 3 is in this embodiment of my invention supplied under pressure, but capillary action as disclosed in my said Patent No. 1,172,233 occurs. It will be observed that immediately upon opening the valve 8 the air is discharged through the passages 31, 32 and hence very slightly prior to the movement of the diaphragm 47 and consequent opening of the orifice 40. Conversely air will continue to issue through passages 31, 32 for a slight

interval after the movement of the diaphragm 47 to close the orifice 40, thus insuring the atomization of the last particle of the coating material.

- 5 In Fig. 3, I have shown a second embodiment of my invention, namely, one wherein the coating material is carried in a container secured to and forming a part of the tool or appliance. Otherwise the structure
 10 represented in Fig. 1 is substantially the same as that already described and need not be referred to in detail, since the same numerals are employed where the construction is the same or substantially the same.
 15 In that embodiment of my invention shown in Fig. 3, the container for the paint or other coating material is indicated at 60, it having a flanged upper end 61 overlying which is a packing ring 62 and below which is a ring 63 which may be clamped or held in any suitable way against the under side of the flange 61. The cover is indicated at 64 and is desirably integrally formed with the body portion 65 which has
 20 a vertical passage 66 into the lower end of which is threaded a pipe 67 extending desirably nearly to the bottom of the container 60 and through which the paint or other coating material is supplied to the passage
 25 36, and hence into the space within the cap 38. The body 65 is provided with an air supply opening 68 into which is threaded a nipple 69 and onto the protruding end of which is threaded the handle member 70
 30 which when threaded into place as described is secured in position by a screw 71 extending through the cover portion 64 and into the said handle portion 70. The means for heating the air or other motive agent is desirably the same as that shown in Fig. 1 and
 35 need not be particularly described and the valve member 30 is also substantially the same and is controlled by a diaphragm 47 in substantially the same manner and need not be further described.
 40 The lower portion 72 of the handle receives a pipe 73 by which air or other motive agent is supplied under pressure to a passage 74 which is in communication with
 45 a valve chamber 75 receiving a bushing 76 threaded into the handle and having a valve seat 77 for a valve 78 normally held closed by a coil spring 79. The stem 80 of said valve extends through suitable packing 81 in a socket or recess in the end of the bushing 76 and takes against a trigger-like operating lever 82 pivoted at 83 upon the under side of the part 70. The bushing 76 is provided with a passage 84 by which the
 50 air, when the valve 78 is opened, is admitted into the passage 85 and thence through the space 19 about the heating coil 21.
 55 Preferably I provide means for placing the coating material in the container under
 60 pressure of the motive agent. To this end,
 65

as shown in Fig. 4, the cover 64 is provided with an opening 86 which receives an exteriorly threaded nipple 87 having an axial passage 88 within an enlarged portion of which is seated a spring-controlled non-return valve 89 to prevent return of the motive agent from the container. Said opening 86 communicates with a passage 90 extending transversely of the body member 65 and opening into the main air or motive agent chamber 20. The flow of air through said passage 90 is controlled by a valve 91 threaded in a bushing 92 which in turn is externally threaded for engagement in the body portion 65 of the tool. Also in communication with the transverse passage 90 is a vertical passage 93 having a restricted lower end in which seats a spring-controlled valve 94. Said vertical passage 93 receives an externally threaded sleeve or bushing 95 having an axial passage 96 opening at its upper end to the atmosphere and within which the spring 97 of said valve 94 is seated. In this manner air under pressure is admitted from the main chamber 20 through passages 90 and 88 to the container, the amount and pressure of which admitted air may be controlled or shut off entirely by means of the valve 91. The spring valve 89 prevents the escape of any particles of coating material through the passage 88. The valve-controlled passage 93 opening to the atmosphere provides a safety vent to relieve against excess pressure of the motive agent, the pressure of the spring 97 upon the vent valve 94 being adjustable and preferably regulated to permit said valve to open to relieve against pressure in excess of the maximum desired to be built up in the container or in the main air chamber.

Having thus described one illustrative embodiment of my invention I desire it to be understood that although specific terms are employed they are used in a generic and descriptive sense and not for purposes of limitation, the scope of the invention being set forth in the following claims.

1. A tool for applying coating comprising a body having passages for coating material and for air under pressure, a hand valve for controlling the entrance of air under pressure into the tool, a valve stem having an axial air passage therein and mounted for reciprocating movement in an air chamber of the tool, a stationary, flexible diaphragm operatively connected with said valve stem and exposed to air pressure at one side only thereof, means to hold said diaphragm stationary in the body, and spring means tending to flex said diaphragm against the pressure of the air.

2. In a tool for applying coating having a body provided with passages for coating material and for air under pressure, a coating material control valve having a stem

- 4
- mounted for reciprocating movement in said body, and an air-actuated flexible, spring-returned diaphragm adjustably connected with said valve stem and exposed to air pressure only at the side opposite the said spring and means fixedly to secure said diaphragm with relation to said body.
3. In a tool for applying coating having a body provided with passages for coating material and for air under pressure, a coating material control valve having a stem mounted for reciprocating movement in said body, a flexible diaphragm fixedly secured in position with respect to said body and operatively connected with said valve stem and exposed to air pressure upon one side only, and resilient means tending to move said diaphragm against the pressure of the air, said resilient means being adjustable whereby said diaphragm is adapted for use over a wide range of operating air pressure.
4. In a tool for applying coating having a body provided with passages for coating material and for air under pressure, a coating material control valve having a stem mounted for reciprocating movement in said body, a flexible diaphragm exposed to air pressure upon one side only and operatively connected with said valve stem, a cap-like member securing said diaphragm in fixed position in said body and adjustable spring means carried by said cap-like member tending to flex said diaphragm against the pressure of the air.
5. In a tool for applying coating having a body provided with passages for coating material and for air under pressure, a coating material control valve having a stem mounted for reciprocating movement in said body, a flexible diaphragm exposed to air pressure upon one side only and operatively connected with said valve stem, a cap-like member securing said diaphragm in fixed position in said body, adjustable spring means carried by said cap-like member tending to flex said diaphragm against the pressure of the air, and an adjustable stop also carried by said cap-like member for limiting the rearward movement of said diaphragm.
6. In a tool for applying coating having a body provided with passages for coating material and for air under pressure, coating material control mechanism including a valve stem mounted for reciprocating movement in an air passage of said body and a flexible diaphragm fixedly secured in position with respect to said body and operatively connected with said valve stem and spring means to flex the same in one direction, said coating material control mechanism being removable as a unit rearwardly of said body.
7. A tool for applying coating comprising a body having passages for coating mate-
- rial and for air under pressure, a manually operable valve for controlling the entrance of air under pressure into the tool, and coating material control means including a valve having a stem provided with an axial air passage and mounted for reciprocating movement in an air chamber of the tool, and a flexible air-actuated spring-returned diaphragm fixedly mounted in said air chamber, said valve stem being secured at its inner end to said diaphragm.
8. A tool for applying coating comprising a body having passages for coating material and for air under pressure, a manually operable valve for controlling the entrance of air under pressure into the tool, coating material control means including a valve having a stem provided with an axial air passage and mounted for reciprocating movement in an air chamber of the tool, said valve stem engaging at the inner end thereof an air-actuated spring-returned diaphragm mounted in said air chamber, and air heating means in said body past which flows the incoming air under pressure.
9. In a tool for applying coating having a body provided with passages for coating material and for air under pressure, the latter including an elongated chamber, means in said chamber for heating the air passing therethrough.
10. In a tool for applying coating having a body provided with passages for coating material and for air under pressure, said air passage including a tubular chamber formed in said body, and means including an electrical resistance coil in said chamber for heating the air passing therethrough.
11. In a tool for applying coating having a body provided with passages for coating material and for air under pressure, means in said body for heating the inflowing air.
12. A tool for applying coating comprising a container, a cover and a tool proper formed with the cover and having a motive agent chamber therein and a passage leading therefrom to said container, a non-return valve positioned in said cover in communication with said chamber through said passage for admitting a motive agent under pressure to the container above the coating material therein, valve means for controlling or shutting off entirely the flow of motive agent into the container, past said non-return valve and a safety valve also in communication with said passage for relieving against excess pressure of the motive agent.
13. Means for applying coating comprising in combination, a container for the coating, a cover therefor, a paint gun body integral with said cover and having passages for coating material and for air under pressure, a laterally extending handle portion having an air passage communicating with the air passage of said gun body, and means

in said air passage of the handle portion for heating the inflowing air.

14. In a tool for applying coating having a body provided with passages for coating material and for air under pressure, coating material control mechanism including a valve stem mounted for reciprocating movement in an air passage of said body, said valve stem having an axial opening therein and extending to the discharge end thereof, and a flexible diaphragm operatively connected with said valve stem and fixedly secured in position with respect to said body, said coating material control mechanism being removable as a unit rearwardly of said body.

15. In a tool for applying coating having a body provided with passages for coating material and for air under pressure, coating material control mechanism including a valve stem mounted for reciprocating movement in an air passage of said body, said valve stem having an axial opening therein and extending to the discharge end thereof, and a flexible diaphragm operatively connected with said valve stem and fixedly secured in position with respect to said body, said diaphragm being exposed to air pressure at one side only, there being spring return means at the other side of the diaphragm, said coating material control mechanism being removable as a unit rearwardly of said body.

16. In a tool for applying coating having a body provided with passages for coating material and air under pressure, the coating material control mechanism including a valve stem mounted for reciprocating movement in an air passage of said body, a flexible diaphragm operatively connected with said valve stem and fixedly secured in position with respect to said body, said diaphragm being exposed to air pressure at one side thereof only, there being spring return means at the other side of said diaphragm, said coating material control mechanism being removable as a unit rearwardly of said body.

17. A tool for applying coating comprising a container, a cover and a tool proper carried by the cover, said cover and tool proper being integrally formed and provided with a passage 90, three valves 89, 91, 94 located in proximity to and controlling the flow through said passage 90 for the purpose set forth.

18. Means for applying coating comprising in combination, a container for the body, a cover therefor, a paint gun integral with said body and having passages for coating material and for air under pressure, valve means in said body and controlling the coating material, a laterally extending handle portion structure distinct from the gun body and having passages therein for the air un-

der pressure, and a pipe or nipple 68 for securing the handle to the gun body and through which the air under pressure flows into said gun body and means in said handle for heating the air on its passage to said body.

19. A tool for applying coating having a body provided with passages for coating material and for air under pressure, said tool having a handle 70 with a heating element receiving chamber therein, the wall of said chamber having a spiral flange receiving said heating element and causing the air to circulate thereabout on its passage to the point of discharge.

20. A tool for applying coating having a body provided with passages for coating material and for air under pressure, said tool having a handle with a heating element receiving chamber therein, the wall of said chamber being constructed and arranged to cause the air to take a circuitous course along said heating element on its passage to the point of discharge.

21. Means for applying coating comprising in combination, a container for the coating, a cover therefor, a paint gun body integral with said cover and having passages for coating material and for air under pressure, the air passage being sufficiently enlarged to receive air heating means, air heating means in the enlargement of said air passage, valve means in said body to control the flow of the coating material, and a laterally extending handle portion structurally distinct from but secured to the said body and having valve control means for introducing air under pressure to said air passage of the gun body.

22. A tool for applying coating having a body provided with passages for coating material and for air under pressure, said air passage including a chamber formed in said body, and means including an electrical resistance coil in said chamber for heating the air passing therethrough.

23. A tool for applying coating comprising a container, a cover and a tool proper carried by the cover, said tool having a chamber 20, means for introducing air into said chamber, a nozzle, and means to permit the passage of air from said chamber 20 to said nozzle, a passage 90 in communication with said chamber 20, a vent valve 94, a regulating valve 91 and a non-return valve 89 all in communication with said passage 90.

24. A tool for applying coating comprising a container, a cover and a tool proper integral with said cover and having a relatively narrow upright chamber 20 in communication with the source of air supply and also with the point of air discharge from the tool, a passage 90 in communication with the chamber 20, a passage 88 in communication with the chamber, a non-re-

turn valve 89 controlling said passage and a regulating valve 91 controlling said passage 90.

25. In a tool for applying coating, said tool provided with passages for coating material and for a motive agent under pressure, means carried by said tool for heating the motive agent passing therethrough.

26. An atomizing device comprising a nozzle, a tube for conducting fluid to said nozzle, and a heating element located in said tube.

In testimony whereof, I have signed my name to this specification.

HERBERT W. DAY.
